DESIGN FOR A DRESS

Claire McCardell, New York, N. Y.

Application May 17, 1941, Serial No. 100,995

Term of patent 3½ years

To all whom it may concern:

Be it known that I, Claire McCardell, a citizen of the United States of America, residing in New York city, county of New York and State of New York, have invented a new, original, and ornamental Design for a Dress, of which the following is a specification, reference being had to the accompanying drawing, forming part thereof, wherein—

I claim:

The ornamental design for a dress, substantially as shown.

CLAIRe McCARDELL,
